UNITED STATES PATENT OFFICE

ELIJAH L. FLOYD, OF CINCINNATI, OHIO, ASSIGNOR TO THE ADLER UNDERWEAR AND HOSIERY COMPANY, OF CINCINNATI, OHIO, A CORPORATION OF OHIO

KNITTING MACHINE

Application filed February 27, 1930. Serial No. 431,785.

This invention relates to improvements in knitting machines of the general type disclosed in the patents to F. B. Wildman, #613,346, and McMichael and Wildman, #508,965, wherein vertical knitting needles are reciprocably mounted in spaced relation upon a rotating needle cylinder, or needle drum, interiorly of which the knitted material is formed. As said needles are moved in a circular path by the rotary needle cylinder or drum, they are actuated by cams to take the thread from one or more suitable thread guides or feeds for forming the fabric, said guides being arranged in spaced relation circumferentially of the needle cylinder.

An object of this invention is to provide a novel means for feeding or guiding thread or yarn to the needles during the knitting operation, and for controlling the feeding or guiding means.

Another object is to provide a knitting machine with a novel arrangement of thread guide or feed units, each unit being adapted to supply the knitting needles with different kinds or colors of thread, none of which units will remain idle during operation of the others.

Another object is to provide improved means for simultaneously controlling the operation of all of the thread guides by means of a pattern mechanism and cooperative cam ring.

These and other objects are attained by the means described herein and disclosed in the accompanying drawings, in which:

Fig. 1 is a cross-sectional view looking down upon the machine and showing in plan the invention and its relation to cooperative parts of the knitting machine.

Fig. 2 is an elevational view taken on line 2-2 of Fig. 1.

Fig. 3 is a cross-sectional view on line 3-3 of Fig. 2.

Machines of the type above referred to are adapted to fabricate continuous lengths of tubular material which later are cut to desired lengths and made into various articles, such as covers for hams, bacon slabs and the like. The invention herein disclosed is ap-

plicable to machines of this and kindred types, such, for example, as are employed in the manufacture of sweat shirts, bathing suits and other articles which are woven in a manner similar to that employed in the manufacture of tubular material. For purposes of decoration or identification of products, it has been desirable to provide such articles as are mentioned above, with one or more circumferential spaced bands or stripes of contrasting weave or color. This has been accomplished heretofore by permanently supplying one or more of the thread guides or feeds with thread of the color or weight of which the band or stripe was to be formed, and providing a mechanism whereby that particular guide or feed, and also the others, could be rendered alternately operative and inoperative during the weaving of the material, thereby causing an encircling stripe to be formed at predetermined intervals along said material. Considerable waste of time, however, and also unnecessary wearing of the parts resulted from operating the machine with some of its thread guides or feeds idle at all times. A machine constructed in accordance with the present invention eliminates this loss of time and unnecessary movement of parts, with the result that the efficiency and output of the machine are materially increased.

In the drawings, 5 represents the circular stationary base plate or frame of a knitting machine in which is rotatably supported a needle cylinder or drum 6, known also as the knitting head. The needle cylinder is provided on its convex surface with a plurality of vertical spaced channels or needle guides 7, each of which supports a knitting needle 8. The needles are adapted for reciprocatory movement within the needle guides, and such movement is effected by means of the usual cams 9 disposed in the circular path of movement of the needles, in a manner well known in the art. Each needle 8 is provided on the upper end thereof with a hook 10, and a pivoted latch member 12 cooperating therewith in the usual manner for interknitting of the threads. The manner in which the fabric is formed by the action of the needles is well

known, and need not be described in detail to convey a clear understanding of the present invention.

A stationary shaft or standard 13 is disposed axially of the needle cylinder and carries a thread cutting member 14 which may be in the form of a band saw bent to form a circular cutter. The toothed cutter 14 is supported upon arms 15 extending radially of the shaft or standard, the teeth 16 thereof being disposed upwardly. The teeth terminate in a plane slightly below the upper annular edge 17 of the needle cylinder, along which edge the knitted material is formed. The function of saw or cutter 14 will be explained in detail after the description of the thread guiding or feeding mechanism.

As shown in Fig. 3, the base plate or frame 5 is provided with cam blocks 20 which support the cams 9 and between which cams the extension 21 of the needles may ride during rotation of the needle cylinder. The cams are arranged to raise and lower the needles as they move along the track. Externally of the base plate or frame is provided an annular cam ring supporting surface or track 18 lying preferably in a horizontal plane. The track 18 is adapted to support an annular cam ring 23 the upper surface 24 of which carries a series of spaced upwardly extending cams 25. Each cam 25 is provided with opposed inclined faces 26 and 27 which are adapted, upon movement of the cam ring, to lift any one of the thread guide actuating rods 28, 29 and 30.

Upon the vertical cylindrical wall 19, which extends upwardly from the cam supporting surface 18 and guides the cam ring, are mounted a series of brackets 31 corresponding in number to the number of cams 25. Bolts or screws 32 may be utilized for securing the brackets upon the wall 19. Each bracket has a radially outwardly extending perforated portion 33, and an upwardly extending thread guide support arm 34. The perforations are indicated by 280, 290 and 300, and they provide guiding means or bearings for the actuating rods 28, 29 and 30, respectively. The upper end 35 of each support arm 34 carries a stud shaft 36 which extends in parallelism with the portion 33 of the bracket. Upon the stud shaft are mounted for rocking movement the thread guide members 37, 38 and 39 each of which has a perforation 40 through which the threads 41, 42, and 43, respectively, may be fed. The thread guide members each have at one end thereof a pivot 44 whereby they may be pivotally connected to their respective actuating rods. By employing spacer members 45 in connection with the pivot pins 44, the members 37, 38 and 39 may be disposed in close side by side parallel relationship, as shown in Fig. 2. The spacer members obviously 65 may be dispensed with by properly bending

the upper ends of the actuating rods toward one another, if desired. The purpose of closely grouping the thread guide members is to insure the feeding of thread therefrom to the needles at or near the peak of upward movement of the needles, as indicated by the dashed line 46. Line 46 indicates the relative heights of the needles as determined by the needle controlling cams 9.

As stated before, the threads 41, 42 and 43 may be of different colors and it may be desired to knit the fabric product using first one color of thread and then another. For example, as shown in Figs. 2 and 3, the guides feeding the threads 41 and 42 are raised or inoperative, relative to the needle hooks, and thread 43 is being fed to the needles. When it is desired to feed the thread 42 instead of thread 43, the cam ring 23 is moved to the left whereby to raise the actuating rod 29 and lower the actuating rod 30. The thread guide 39 thereupon will be moved to the raised or inoperative position, and guide 38 will be lowered to operative position. Similarly, if it is desired to feed the thread 41, the cam ring is rotated farther to the left, whereupon the actuating rod 28 will be moved to the raised or operative position and rods 29 and 30 will be in the lowered or inoperative position. The particular means used for moving the cam ring is immaterial to the invention wherefore it is considered sufficient to state that a pattern mechanism 47 of any suitable type, one form of which is disclosed in the above mentioned Patent No. 508,965, may be employed. As shown in Fig. 1, a movable part 48 of the pattern mechanism may be connected to the cam ring by means of a pivotally mounted connecting rod 49.

It is of importance that the cam 25 on the cam ring 23 be arranged to momentarily effect the feeding of two of the threads during the change from one thread feed to another, so that the continuity of the stitching will not be interrupted. It should be readily apparent that a flaw in the material would result if no thread were fed during the change from one color or kind of thread to the other. To obviate this difficulty, the base of the cam 25 is of a length slightly less than the distance between the endmost rods 28 and 30, and the length of its top surface is slightly greater than the distance from one of the endmost rods to the rod 29. The rod 29 is shaped so as to present an under surface or cam surface 50 of greater size than that of rods 28 and 30, so that the cam 25 may strike the cam surface and raise the rod 29 before the lowering of rod 30 (Fig. 2). From the foregoing, it should be apparent that movement of cam 25 to the left, (Fig. 2), will cause the raising of the rod 29 before lowering of the rod 30. During this short interval of time, both of the threads 42 and 43 will be fed to the needles,

thereby providing for a continuous feed of thread. The cam 25, when positioned to feed the thread 42 controlled by rod 29, lay entirely between the rods 28 and 30. To feed the 5 thread 41, the cam ring is moved farther to the left for raising rod 28 and lowering rod 29. During this interval of change, there is again effected a double feeding of threads 41 and 42 to preserve the continuity of the 10 stitching.

In Fig. 2, 51 represents a bracket or upright secured to the machine frame by means of bolts or the like, which provides a support for eyelets 52 which receive the thread 15 from suitable sources of supply, not shown. The bracket carries also a needle latch retainer 53 which serves to maintain the latch of the needle in proper position during formation of the stitches. The needle cylinder 20 may be rotated by any suitable means such as a gear 54 driven by a pulley 55 or other source of power, the gear being in mesh with gear teeth 56 on the lower peripheral edge of the cylinder. A take-up device is indicated by 25 57 and consists of the usual pair of oppositely rotating rolls moving bodily with the needle cylinder. The take-up device receives the knitted fabric as it leaves the needle cylinder. It will be understood that the pattern mechanism 30 may be operated by any suitable means such as a cam 58 on the revolving needle cylinder adapted to strike an arm 59 extending from the pattern mechanism and having ratchet or other means for producing intermittent 35 of the pattern mechanism.

A spring 60 surrounding the needle cylinder maintains the needles in a proper position within their respective channels.

The operation of the device is as follows: 40 as will be understood from the foregoing description, the thread feeding units consisting of the guides 37, 38 and 39 and their respective actuating rods, are mounted upon the knitting machine frame about the needle cylinder 45 in spaced relationship. Each of said units has associated therewith the proper cams 9 for moving the needles to a position such that they may receive the thread fed by the guide means 37, 38 and 39. As shown in Figs. 2 50 and 3, the cam 25 is in a position beneath the actuating rod 30, which serves to position the thread guide 39 in proximity with the loops of the knitting needles. As the needle cylinder 55 revolves, the knitting process continues, making use of the thread 43 which, for purposes of explanation, may be referred to as blue thread. The pattern mechanism, being operated by the rotating needle cylinder, will be operated upon predetermined movement thereof by the cam needle cylinder, to 60 actuate the connecting rod 49 which is pivoted to the cam ring 23. Upon movement of the cam ring 23 by the pattern mechanism, the cam 25 will be advanced to a position between the actuating rods 28 and 30. Said

movement of the cam causes the withdrawal of thread guide 39 from the operative position, and places the white thread guide 38 in the operative position. As stated before, the cam 25 is arranged relative to the actuating rods, so as to momentarily effect the feeding both the blue and white threads during the interval of change of feed. While the cam maintains the actuating rod 29 in the raised position, the knitting will continue with white thread instead of blue. The amount of knitting to be performed with white thread, is determined by the pattern mechanism, and upon predetermined movement thereof the cam 25 is again advanced so as to lift the actuating rod 28 which controls feeding of, for instance, a red thread. During the change from white to red thread, the lowering of the actuating rod 29 is delayed slightly, because of the design of the cam 25 and enlarged cam shaft 50 of the rod, to feed a small amount of white thread while feeding of the red thread, being started. Upon completion of a predetermined period of knitting with red thread, the pattern mechanism again operates for feeding either white or blue thread.

Upon changing from one color of thread to another, it is necessary to cut off certain threads which extend from the knitted material to the central shaft 13. The band-like saw 14, bent into circular shape and provided with the upwardly extending teeth 16 is stationarily mounted within the needle cylinder to perform the cutting operation. The saw 100 is supported upon the radially extending arms 15 which are mounted upon the stationary shaft 13. The teeth of the cutter member or saw lie in a plane slightly below the upper edge of the knitting needle, so that the threads will not be cut immediately after the 105 change of feed. The cutting of the threads occurs after several revolutions of the needle cylinder following the change of feed.

Machines constructed in accordance with the present invention have greater efficiency and production than the type of machine heretofore used in the manufacture of knitted articles such as are mentioned herein. This is due to the arrangement of thread guides or feeds in such manner that several of them may be actuated by a single means. In the older type of machines, each thread guide had in association therewith a needle raising and lowering cam which performs useless work during the interval that its corresponding thread guide was inoperative. In the device of this invention, however, there is always a feed of thread operating to supply the needles at all points about the needle cylinder where the needles are disposed in receiving position.

What is claimed is:

1. In a device of the class described the combination of a frame, a needle cylinder ro-

- tatable relative to the frame, needles carried by the cylinder, each needle having a thread receiving portion, a plurality of thread guides for the needles each thread guide being movable to operative and inoperative positions relative to the thread receiving portions of the needles, a single movable cam for cooperation with the thread guides for movement of the thread guides to the operative and inoperative positions, said cam being arranged to move an operatively positioned thread guide to the inoperative position after having first moved another thread guide to the operative position.
- 15 2. In a device of the class described the combination of a frame, a needle cylinder rotatable relative to the frame, needles carried by the needle cylinder and having thread receiving portions thereon, and a plurality of thread feeding units for supplying various kinds of threads to the thread receiving portions of the needles said units each comprising a central actuating rod and a pair of actuating rods one disposed on each side of the central actuating rod, said rods all being mounted for reciprocation relative to the frame, a thread guide cooperating with each actuating rod and movable by the rods to operative and inoperative positions relative to the needles, and means associated with each thread guide unit and cooperating with the actuating rods for reciprocation of the rods to selectively place the corresponding thread guides of each unit into operative positions.
- 30 3. In a device of the class described the combination of a frame, a needle cylinder rotatable relative to the frame, needles carried by the needle cylinder and having thread receiving portions thereon, and a plurality of thread feeding units for supplying various kinds of threads to the thread receiving portions of the needles said units each comprising a central actuating rod and a pair of actuating rods one disposed on each side of the central actuating rod, said rods all being mounted for reciprocation relative to the frame, a thread guide cooperating with each actuating rod and movable by the rods to operative and inoperative positions relative to the needles, and a plurality of simultaneously movable means, one being associated with each thread guide unit, for effecting movement of corresponding thread guides of each unit to an inoperative position after having first effected movement of other corresponding thread guides to the operative position.
- 45 4. In a device of the class described the combination of a frame, a needle cylinder mounted for rotation relative to the frame said needle cylinder having an annular portion along which knitted material is formed, knitting needles carried by the needle cylinder for performing the knitting operation,

means for feeding thread to the knitting needles, a standard disposed substantially axially with respect to the needle cylinder and about which standard certain portions of the knitting thread may be wound during the knitting operation, and a thread cutting member substantially encircling the standard and disposed between the standard and the said annular portion of the needle cylinder.

5. In a device of the class described the combination of a frame, a needle cylinder mounted for rotation relative to the frame said needle cylinder having a portion along which knitted material is formed, knitting needles carried by the needle cylinder for performing the knitting operation, means for feeding thread to the needles, a standard serving as a spool upon which certain portions of the knitting thread may be wound during the knitting operation, and a thread cutting member disposed between the standard and the portion of the needle cylinder along which the knitted material is formed, said thread cutting member lying in a horizontal plane located below said portion of the needle cylinder and substantially encircling the standard.

In testimony whereof, I have hereunto subscribed my name this 25th day of February, 1930.

ELIJAH L. FLOYD.
